CARL E. GRUNSKY, OF SAN FRANCISCO, CALIFORNIA.

AUTOMATIC MOVABLE DAM.

1,179,520.

Specification of Letters Patent. Patented Apr. 18, 1916.

Application filed November 17, 1914. Serial No. 872,551.

To all whom it may concern:

Be it known that I, CARL E. GRUNSKY, a citizen of the United States, residing in the city and county of San Francisco and 5 State of California, have invented new and useful Improvements in Automatic Movable Dams, of which the following is a specification.

This invention relates to dams, and per- 10 tains especially to an automatically oper- able wicket or shutter adapted when the body of confined water in the dam reaches a predetermined level to release a surplus volume of water without any impairment 15 to the dam.

The invention consists of the parts and the combination and construction of parts, as hereinafter more fully described and claimed, having reference to the accompany- 20 ing drawings, in which—

Figure 1 is a cross sectional view showing the application of the invention. Fig. 2 is an elevation of the down-stream face of the shutter.

25 A represents a dam or embankment; 2 a spillway and 3 the movable wicket or shutter arranged in the spillway and constituting the present invention. This shutter is adapted to be normally supported in up- 30 tilted position, as shown in full lines Fig. 1, so as to retain the body of water behind it, and to be turned down into horizontal dotted line position Fig. 1, automatically by the rise of the water in the dam to a 35 point which might prove dangerous to the structure, or to a level above which, for other reasons it may not be desired to have the water rise. This supporting and auto- 40 matic tilting of the wicket may be accom- plished by any appropriate means. In the present instance I have shown it supported by struts 4, arranged down-stream, having their lower ends pivotally supported at 5 and their upper ends pivoted at 6 to the 45 back of the shutter. The supporting points 6 at which the struts meet the shutter are at such elevation above the lower edge of the shutter that when the water up-stream from the dam reaches or closely approaches the 50 top of the shutter the water pressure against the face of the shutter above the points 6, will be very nearly equal to the water pres- 55 sure against the face of the shutter below the points 6; the shutters being in equilib- rium or very nearly so, when the water is at its crest. This equilibrium is overcome

by allowing a sufficient quantity of water from the dam to flow into a pocket formed in the wicket above the centers 6, in a manner now to be described.

60 Shutter 3 comprises a rather flat, hollow box-like structure, having an enlarged water compartment or series of compartments 7 at the top which will be filled when the water reaches the crest thereof, and which will then overbalance and tilt the shutter. The inlet or inlets 8 to the compartments 7 are on the up-stream side of the shutter, and are of ample capacity and are placed below the water surface, so that trash floating on 70 the water will not be carried into the shutter. Small openings 9 on the down-stream side or back of the shutter allow the escape of air as the shutter fills with water. Water entering at 8 is directed upwardly within 75 the shutter through suitable ducts 9' into the compartment or compartments 7 and may thence flow down through the shutter gradually filling the latter, and eventually 80 escaping through a restricted opening 10 in the bottom of the shutter at the back thereof; a baffle 11 at the bottom of the shutter serving to check the flow of water and preventing a too rapid escape at 10. The lower 85 edge of the shutter is inclined downwardly and forwardly as shown at 12, and is sup- 90 ported in up-tilted position against a suit- able ledge or abutment 13 in the bottom of the spillway; ledge 13 forming the rear wall of a recess whose inclined bottom 14 is nor- 95 mal to the face of the shutter when the latter is in up-tilted operative position. Anti-friction rollers 15 are provided on the lower end of the shutter to run on the in- 100 clined bottom 14 and are so arranged that when the shutter leaves its seat against the ledge or wall 13 water will flow under the shutter, aiding the water already in the re- cess or pocket 16 in the spillway in which the shutter will lie when down, to break the fall of the shutter. Pockets 17 are ar- 105 ranged in the spillway bed to receive the struts 4 when the parts are in collapsed hor- 110 izontal position.

The parts being supported in operative position as shown in Fig. 1, the operation will be as follows: The water rising above a predetermined level will flow in large quantities through the slot openings 8 more rapidly than it escapes at 10, gradually fill- 110 ing the shutter and the enlarged water compartment 7. As the filling of water com-

partment or compartments 7 progresses, the center of gravity of the shutter will gradually be shifted to a point down-stream from the supporting centers 6 at which the struts 5 connect with the shutter, whereupon the bottom of the shutter will move forward up-stream away from its supporting sill 13. Water will thus rush under the lower edge of the shutter below the rollers 15, and will 10 also flow over the top of the shutter. The shutter will thus be forced down by water pressure from above to a horizontal position in the pocket 16 which is provided to receive it, and water will flow over it without obstruction. The shutter is constructed of some material heavier than water and will remain in a flat position when down and filled with water. Any appropriate means may be employed to raise the shutter 15 again into operative position. In the present instance I have shown the relief openings 10, which are arranged near the two ends of the shutter and adapted to register with air conduits 18 adapted to supply air 20 under pressure from any suitable source of supply, not necessary here to be shown. With air pipes 18 and openings 10 in register, air under pressure is admitted to the interior of the shutter until enough water 25 has been replaced by air to float the shutter; a baffle 19 being arranged in the bottom of the compartment 7 so that more air will be held in the part of the shutter below the centers 6 than in the part above. The baffles 11 and 19 form with the side and front 30 walls of the shutter a compartment which confines the air therein to render the shutter buoyant, the water being expelled under the baffle 19. When the shutter is floated by 35 air to the water surface, power is applied to the opposite edge or crest edge of the shutter by suitable means, as a chain 20. Under the influence of this force and of the water pressure on the face of the shutter below 40 points 6, the bottom edge of the shutter will be forced against its seat 13, and will remain there until the water again rises to its crest. The upward movement of the shutter is checked by suitable means, as locating 45 the outside supporting struts, in a recess 50 22 in the abutment walls of the spillway, so arranged that when the necessary height has been reached by the struts, it will be checked.

55 It will be manifest that various changes in details of construction may be made without departing from the principle of the invention.

Having thus described my invention, what 60 I claim and desire to secure by Letters Patent is—

1. An automatic movable dam comprising in combination, a shutter, a plurality of struts pivotally connected at their lower 65 ends to fixed supports and at their upper

ends to the shutter, said struts adapted to normally hold the shutter in an upright position, means controlled by a predetermined high water level for overbalancing the shutter above the strut bar pivots and lowering 70 it into a horizontal position in a receiving pocket, said means comprising a chamber formed in the interior of the shutter, and means for admitting water to said chamber.

2. An automatic movable dam comprising 75 in combination, a hollow shutter, a plurality of struts pivotally connected at their lower ends to fixed supports and at their upper ends to the shutter, said struts adapted to normally hold the shutter in an upright 80 position, means controlled by a predetermined high water level for overbalancing the shutter about the strut bar pivots and lowering it into a horizontal position in a receiving pocket, said means comprising an 85 upper and lower compartment formed in the interior of the shutter, means for admitting water to said compartments, means for raising the shutter, said means comprising an air connection for admitting air into the 90 lower compartment to make the shutter buoyant to partly raise same, a lifting chain for raising the shutter the remaining distance to upright position, and means for discharging the water remaining in the 95 shutter when this is raised.

3. An automatic movable dam, or dam crest, consisting of a hollow shutter, supporting means engaging the shutter at points of support so that when the water 100 up-stream from the dam reaches the top of the shutter the water pressure against the face of the shutter below said point of support will approximately counterbalance the pressure of the up-stream water on the face 105 of the shutter above said points of support, means for an inflow of water into the hollow shutter at a predetermined elevation of the up-stream water surface, whereby the shutter will be overbalanced and will automatically assume a horizontal position falling into a recess prepared to receive it thereby releasing the up-stream water.

4. An automatic movable dam, or dam crest, consisting of a hollow shutter, supporting means engaging the shutter at points of support so that when the water up-stream from the dam reaches the top of the shutter the water pressure against the face of the shutter below said points of support will 110 approximately counterbalance the pressure of the up-stream water on the face of the shutter above said points of support, means for an inflow of water into the hollow shutter at a predetermined elevation of the up-stream water surface, whereby the shutter will be overbalanced and will automatically 115 assume a horizontal position falling into a recess prepared to receive it thereby releasing the up-stream water and means for sup- 120

plying air to the interior of the shutter when the shutter is down, which by displacing the water contents of the shutter will cause the shutter to float and rise.

5. In an automatic movable dam, or dam crest, consisting of a hollow shutter, supporting means engaging the shutter at points of support so that when the water upstream from the dam reaches the top of the 10 shutter the water pressure against the face of the shutter below said point of support will approximately counterbalance the pressure of the up-stream water on the face of the shutter above said point of support, 15 means for an inflow of water into the hollow shutter at a predetermined elevation of the up-stream water surface, whereby the shutter will be overbalanced and will automatically assume a horizontal position falling 20 into a recess prepared to receive it thereby releasing the up-stream water, means for supplying air to the interior of the shutter when the shutter is down, which by displacing the water contents of the shutter will 25 cause the shutter to float and rise, and means for applying power to turn the shutter on said points of support when it is afloat, so that the shutter will resume an upright or nearly upright position and will again act as 30 a dam.

6. A movable dam comprising a hollow shutter, a rigid strut connected at one end to the shutter for pivotal movement only and adapted for holding the latter operative 35 whereby on the admittance of water into the shutter the latter will overbalance on its pivotal mounting for tilting, the shutter being provided with an opening for admitting water at a predetermined level.

40. 7. A movable dam comprising a shutter provided in its upper part with a water compartment and means for admitting water thereto for causing a movement of the shutter to inoperative position, and 45 means for supporting the shutter in an operative position and connected pivotally to the latter at a point below the water chamber.

8. A movable dam comprising a shutter,

and means pivotally supporting the shutter 50 between its ends in upright position, the shutter being formed with a water chamber extending above and below the pivotal mounting and provided above the latter with an enlarged water compartment for receiving water to effect a tilting of the shutter. 55

9. A movable dam comprising a shutter, and means pivotally supporting the shutter between its ends in upright position, the shutter being formed with a water chamber 60 extending above and below the pivotal mounting and provided above the latter with an enlarged water compartment for receiving water to effect a tilting of the shutter, means for admitting water to the chamber, 65 and drain means provided for the chamber of the shutter below the pivotal mounting.

10. A movable dam comprising a shutter, and means pivotally supporting the shutter 70 between its ends in upright position, the shutter being formed with a water chamber extending above and below the pivotal mounting and provided with an entrance passage extending upwardly within the 75 chamber to admit water at a level about the mouth of the passage.

11. A movable dam comprising a shutter, and means pivotally supporting the shutter between its ends in upright position, the 80 shutter being formed with a water chamber extending above and below the pivotal mounting and provided with means for admitting thereto and draining water therefrom, means for discharging the water from 85 the chamber to render the latter buoyant, and a baffle arranged in the chamber adjacent to the water admitting means for confining with the chamber walls the buoyant space during the discharge of the water. 90

In testimony whereof I have hereunto set my hand in the presence of two subscribing witnesses.
